UNITED STATES PATENT OFFICE.

MORLEY LINTON RUTHERFORD, OF LA FAYETTE, INDIANA.

INDOOR-BALL DEVICE.

Application filed September 10, 1924. Serial No. 736,878.

To all whom it may concern:

Be it known that I, MORLEY LINTON RUTHERFORD, a citizen of the United States, residing at La Fayette, in the county of

5 Tippecanoe and State of Indiana, have invented a Device for Playing the Game of Baseball Indoors, to be Known as an Indoor-Ball Device, using certain adaptations of the game to suit the device.

10 It is to be used in gymnasiums or anywhere that groups of people assemble, where such entertainment would be desired and can also be used as a midway amusement device.

15 Any number of people can play the game; sides being chosen and some one keeping the score; the score being kept as in the regular game.

Chairs are placed about the room to serve 20 as bases and the players throw at the device in turn, each player being allowed three throws.

25 Rubber or lightly filled base balls are used so that walls will not be damaged. The person throwing stands from 20 to 25 feet from the device, if room will permit.

30 In the accompanying drawing Fig. 1 is a front elevation of my device showing the position of the blocks and their hinging arrangement, the method of concealing and revealing the various plays, and the supporting frame including ball receptacle.

Fig. 2 is a side elevation showing particularly, supporting foot, catching curtain, and 35 the position of blocks when knocked down.

Fig. 3 is a detail of the setting up attachment.

Fig. 4 is an end view of the setting up attachment.

40 The device consists of a substantial wood frame, the two uprights 19 in Fig. 1 are 2" x 4" material having a base of 1" x 4" material 20 in Fig. 2.

The crosspieces 11 and 12 Fig. 1 beside 45 being a part of the frame serve useful purposes.

50 Crosspiece 11 of 2" x 4" material cut as shown by dotted line at 11 Fig. 2 and having sides of 1" x 4" material, serves as a receptacle for balls, instruction sheets etc.

The crosspieces 12 of 2" x 4" material, 55 cut to allow blocks 1 to 10 Fig. 1 to fall into position 9 in Fig. 2, also serve as a mounting for the blocks and the various plays are shown on the face of these crosspieces 12 as at 8 and 9 Fig. 1 so that when blocks 1 to

10 are in an upright position, the plays are covered by the lower part of the blocks.

The blocks 1, 2, 3, 4, 5, 6, 7, 8, 9 and 10 Fig. 1 are 1 $\frac{1}{4}$ " x 4" x 12" white pine, to prevent splitting, are cut as shown in Fig. 1 and are so balanced that when they are hit by a ball they fall over readily and can be quickly restored to position by setting up attachment 16 in Figures 1 and 2 and Fig. 3. 65

The blocks 1 to 10 are hinged by means of eyebolts 14 Fig. 1; two bolts being used for each block, with a washer on either side of the block, the nuts being counter sunk flush with the face of the blocks. The blocks 70 are hung by means of the eyebolts 14 onto the rod 13 and side play is prevented by the screw eyes 15 which are screwed into the crosspieces 12. The $\frac{5}{16}$ " straight iron rod 13, having a small hole near either end for cotter pin, passes through the eyebolts 14 in blocks 1 to 10 also through screw eyes 15 in crosspieces 12 and extends through the uprights 19 Fig. 1 and is fastened at either end by a countersunk washer and cotterpin 75 18 Fig. 2. The whole making a very satisfactory and secure hinging arrangement. 80

The setting up attachments are $\frac{5}{16}$ " iron rods, Fig. 3 and 16 in Figures 1 and 2, and are fastened to the front of uprights 19 by 85 screw eyes 17 and when lever is pulled forward will raise blocks as is quite clearly shown at 16 and 9 Fig. 2.

The blocks 1 to 10 are placed two inches apart so that it is possible to occasionally 90 knock down two blocks at the same time; this play being designated as a foul ball. The blocks 1 to 10 when knocked down as 8 and 9 Fig. 1 show the other plays as follows;

Block 1; take second base. The player throwing goes to second base.

Block 2; player on first out. The player (if any) on first is out but the play simply counts as a strike against player throwing.

Block 3; take first base. The player throwing goes to first base and any player on first advances to second, and so on.

Block 4; player on third out. This puts player on third, if any, out; simply counts 105 as a strike against player throwing.

Block 5; base on balls. Player throwing goes to first base.

Block 6; error—advance any player one base. Side throwing should advance any 110 player one base that will be to their best advantage.

Block 7; out on second. Player (if any) on second is out, but play simply counts as a strike against player throwing.

Block 8; home run. Player throwing 5 makes home run touching each base and any other players on bases go in home at same time.

Block 9; out. This puts player throwing, out.

10 Block 10; take third base. Player throwing takes third base and any other players on bases advance accordingly.

If no blocks are knocked down so that 15 plays on face of crosspieces 12 can be read, each throw counts as a strike just the same.

It will be noted that count is for or against side doing the throwing.

The setting up feature of the device can be operated by cords from a safe distance 20 in front of device or without cords as players desire.

A detachable and optional feature of the device is a catching curtain (shown by dotted lines 23 and 25) Fig. 2 to catch those 25 balls that would otherwise go through and back of device; it is made of heavy cotton goods and is hung from a $\frac{1}{4}$ " iron rod 21 in Fig. 2 which extends the width of the device, between uprights and is bent at 30 either end to attach to the uprights 19, on the inside, and extend back from uprights six inches, and to hook into screw eyes 22 Fig. 2. The curtain is also fastened at the bottom onto a $\frac{1}{4}$ " iron rod, having a one 35 inch bend at one end and a small hole for cotter pin near the other end; this rod being placed along the top of the rear side of ball receptacle 11 and fastened at either end through screw eyes 24, Fig. 2. The 40 curtain being hung six inches back of the frame does not interfere with the falling of the blocks and also fits snugly against the uprights at either end.

As a midway amusement device the plan 45 is, to offer a first prize for three consecutive home runs and a second prize for three home runs not made consecutively. First base, error, and base on balls, would entitle player to one extra throw; two base hit, two extra 50 throws and three base hit three extra throws: Out or out on first player would lose one extra throw; out on second he would lose two extra throws; and out on third would lose three extra throws. These plays 55 are on the basis of player being allowed three throws for a stated price; extra throws being allowed for first three balls but no extras being allowed on extra throws.

I claim:

60 An indoor ball device for playing the

game of baseball, indoors, comprising a substantial wood frame having two uprights, each of which has a transverse, rectangular foot, for support of device, the two uprights being joined together by five horizontal cross-pieces, the two upper cross-pieces bearing on the face, in permanent lettering, with proper spacing, ten plays, five on each cross-piece, of the well known game of baseball; a box like, ball receptacle comprising the three lower cross-pieces in conjunction with the two uprights; two sets of numbered, balanced, shaped, rectangular blocks, five blocks to each of the two upper cross-pieces comprising a set, said blocks 65 being mounted perpendicularly by a special hinging arrangement, with lower third of block below hinge flat against the face of the cross-piece so that this portion of each block covers one of the plays of baseball, 70 shown on the face of cross-pieces, blocks being so balanced that when the upper portion above hinge, which also extends above cross-piece, is hit by a thrown ball, the block so hit will fall back over the cross-piece at an 75 angle of about 135 degrees, thus exposing one of the various plays, on face of cross-pieces to view of players; a special hinging arrangement for each set of blocks, comprising two eye-bolts in each block, two screw-eyes for each block screwed into top of cross-piece to prevent side play of blocks and a straight iron rod placed just above and parallel with the cross-piece, said rod passing through screw-eyes in cross-piece, 80 through eye-bolts in blocks and extending through uprights and flush with the outside of same, where it is secured by means of a countersunk washer and cotter pin; a setting up attachment for restoring blocks to 85 an upright position, comprising an iron rod for each set, said rod being bent to attach to front of left upright by means of a screw-eye, to extend back on inside of upright, 90 across and forward to front of other upright where it is attached by an other screw-eye, this end of rod extending to outside of upright and being bent to form an upright lever-like handle; a catching curtain, hung from an iron rod which is bent at either 95 end to attach to screw-eyes on inside top of uprights and to extend far enough back of frame to prevent curtain from interfering with the falling of the blocks, the curtain having triangular shaped side flaps which 100 fit snugly against back of uprights and is attached at its lower extremity to the top of the back of ball receptacle, so that balls striking it drop into ball receptacle.

MORLEY LINTON RUTHERFORD.
